UNITED STATES PATENT OFFICE.

CHRISTIAN ALLMAN, OF HUNTINGTON, INDIANA.

DESIGN FOR A BICYCLE CRANK AND SPROCKET-WHEEL.

SPECIFICATION forming part of Design No. 32,702, dated May 22, 1900.

Application filed April 13, 1900. Serial No. 12,774. Term of patent 14 years.

To all whom it may concern:

Be it known that I, CHRISTIAN ALLMAN, a citizen of the United States, residing at Huntington, in the county of Huntington and State 5 of Indiana, have invented and produced a new and useful Design for a Bicycle Crank and Sprocket-Wheel, of which the following is a specification.

Figure 1 is a plan view of a bicycle crank 10 and sprocket-wheel, showing my new design. Fig. 2 is a side elevation of the same.

As shown in the drawings, the leading or material feature of my design consists of a wheel comprising an outer rim, a series of 15 spokes connected to the inner edge of the rim, a central aperture, and a crank-arm extending outward from the face of one of the spokes and outward away from the rim of the wheel. The spokes taper in width as they extend outward to the rim, and the inner end of the crank-

arm conforms to the shape of the face of the spoke and has a rib upon its outer surface, which extends outward and merges into a round crank-arm having an aperture in its outer end. The aperture at the center of the 25 spokes has two flat sides and two curved surfaces. Sprockets are formed on the periphery of the wheel.

Having thus fully described my invention, what I claim is—

The design for a bicycle crank and sprocket-wheel, substantially as herein shown and described.

In testimony whereof I have hereunto set my hand in presence of two subscribing witnesses.

CHRISTIAN ALLMAN.
